UNITED STATES PATENT OFFICE.

LOUIS H. REINHARDT, OF BERGER, MISSOURI.

ANTI-RAIL-SPREADING DEVICE.

1,137,083.

Specification of Letters Patent. Patented Apr. 27, 1915.

Application filed December 9, 1914. Serial No. 876,326.

To all whom it may concern:

Be it known that I, LOUIS H. REINHARDT, a citizen of the United States, residing at Berger, in the county of Franklin and State 5 of Missouri, have invented certain new and useful Improvements in Anti-Rail-Spreading Devices, of which the following is a specification.

This invention relates to railway safety 10 appliances, and more particularly to a rail brace which will effectually prevent spreading of the rails.

An object of the invention is to provide a safety appliance of this character which can 15 be applied to any railroad, and which can be applied either during the course of construction thereof or after the same is completed.

Another object is to provide an appliance which can be easily and quickly placed in 20 position to firmly hold the rails.

With these and other objects in view, the invention consists in the novel features of construction, combination and arrangement of parts as will be hereinafter more fully 25 described, illustrated in the accompanying drawings and claimed.

In the drawings: Figure 1 is a transverse section of a pair of railway rails showing the attachment applied thereto; Fig. 2 is a 30 horizontal section on the line 2-2 of Fig. 1; Fig. 3 is a plan view of one end of the bar and head respectively.

Referring to the drawings by numerals, R-R designate a pair of railway rails 35 which are adapted to be supported upon the usual ties T.

The improved anti-spreading device comprises a rectangularly shaped elongated bar 1 which is adapted to underlie the base 40 flanges of the rails, as is clearly shown in Fig. 1 of the drawings. Integral heads 2 and 3 are formed on the ends and upon the upper face of the bar and these heads are adapted to engage the outer and inner portions respectively of the respective rails.

The head 2 comprises an upright portion 4 for engagement with one side of the web of the rail and this upright portion is held rigid by means of a brace 5. The head 3 50 comprises an extension which is formed upon the upper face of the bar 1 and has a lip 6 which overhangs a recess formed in said head for the reception of one side of the base flange of the rail. The end of the bar 55 adjacent to the head 3 is provided with an upwardly extending lip 7, and this lip has

the inner portion thereof angularly disposed and beveled as shown at 8. A removable head 9, which is of substantially the same construction as the head 2, has its outer end 60 angularly-shaped and beveled as at 10 for engagement with the lip 7.

It will be seen that upon placing the rails in engagement with the heads 2 and 3 and inserting the removable head 9 within the angularly disposed portion of the lip and in engagement with the rail, the said angular portions of the head and bar will cause the head to be clamped tightly against the rail. A bolt 11 may then be inserted 65 through alining openings in the bar and head to prevent accidental removal of the head from the bar.

From the foregoing description taken in connection with the accompanying drawings it is thought that the construction and operation of the device will be clearly understood and while I have herein shown and described one specific form of my invention I do not wish to be limited thereto, except 70 for such limitations as the claims may import.

Having thus fully described my invention what I claim as new and desire to secure by Letters Patent is:—

1. An anti-rail spreading device comprising a bar, said bar having integral heads formed thereon, one of said heads adapted to engage the outer portion of one of the rails, the other head adapted to engage the 90 inner portion of the other rail, said first-mentioned head comprising a base flange engaging portion and a web engaging portion, said web engaging portion adapted to have the upper portion thereof abut the under 95 face of the ball of a rail, an angular lip formed on one end of said bar, said lip being beveled adjacent its angular face, a removable head for engagement with the outer portion of said last-mentioned rail, said 100 head having a beveled portion for engagement with the beveled portion of the lip, and means to prevent accidental disengagement of the removable head from the bar.

2. An anti-rail spreading device comprising a bar, said bar having integral heads formed thereon, one of said heads adapted to engage the outer portion of one of the rails, the other head adapted to engage the inner portion of the other rail, said first 105 mentioned head comprising a base flange engaging portion and a web engaging por-

tion, said web engaging portion adapted to have the upper portion thereof abutting the under face of the ball of the rail, a brace connected between said web engaging portion and said bar, an angular lip formed on one end of said bar, said lip being beveled adjacent its angular face, a removable head for engagement with the outer portion of said last-mentioned rail, said head 10 having a beveled portion for engagement

with the beveled portion of the lip, and means to prevent accidental disengagement of the removable head from the bar.

In testimony whereof I affix my signature in presence of two witnesses.

LOUIS H. REINHARDT.
